Primary Examiner — Ricky Pham(74) Attorney, Agent, or Firm — Sapientia Law Group PLLC; Jeffrey C. Brown, Esq.(57) CLAIM

The ornamental design for a cutlery handle, as shown and described.

DESCRIPTION

FIG. 1 is left side view thereof showing our new design, the right side view being a mirror image of the left side;

FIG. 2 is a rear view of the cutlery handle;

FIG. 3 is a front view thereof;

FIG. 4 is a top view thereof; and,

FIG. 5 is a bottom view thereof.

The broken lines are for illustrative purposes only, and form no part of the claimed design.
